UNITED STATES PATENT OFFICE.

ROBERT J. BOYD, OF DETROIT, MICHIGAN.

HEEL.

1,123,475.

Specification of Letters Patent.

Patented Jan. 5, 1915.

Application filed December 4, 1912. Serial No. 734,824.

To all whom it may concern:

Be it known that I, ROBERT J. BOYD, a subject of the King of Great Britain, residing at Detroit, in the county of Wayne and State of Michigan, have invented certain new and useful Improvements in Heels, of which the following is a specification, reference being had therein to the accompanying drawings.

10 This invention relates to heels for boots or shoes adapted to prevent slipping or skidding and arranged to provide also for a cushion if desired.

15 The invention consists in the matters hereinafter set forth and pointed out in the appended claim.

In the drawings, Figure 1 is a view in perspective of a heel that embodies features of the invention; Fig. 2 is a bottom plan view 20 thereof with the resilient body or block removed; Fig. 3 is a view in section showing the adaptation of the heel for a cushion tread; and Fig. 4 is a view in transverse section showing the arrangement of the heel to 25 prevent slipping.

Referring to the drawings, a body 1 of a heel built of the usual material arranged in lifts, is recessed on its base to receive a cup 2 of thin sheet metal or like material which 30 is secured in place as by screws 3 or like suitable means. The edge portion 4 of the cup is arranged to project a little from the base of the heel when the latter is new and as the latter wears away presents a thin edge 35 which cuts into and holds the heel firmly on an otherwise slippery surface. The cavity of the cup is filled with a body 5 of resilient material adapted to normally project beyond the surface of the heel as a cushion and 40 secured in place by a suitable screw 6 or the

like. This may be replaced in icy weather by a body 7 whose outer face is dished or concaved to allow the margin of the cup to readily act as a spur or cleat.

The heel is provided with both filling 45 members which may be interchangeably secured in the cup according to the season and the wearer's preference. As the body of the heel wears away more readily than the margin of the cup the latter always presents a 50 sharp cutting edge that enters ice or the like on slippery surfaces and prevents slipping in any direction.

Obviously, changes in the details of construction may be made without departing 55 from the spirit of my invention and I do not care to limit myself to any particular form or arrangement of parts.

What I claim is:—

A heel having a concave recess formed centrally in the bottom thereof, a metallic cup snugly engaging the walls of said recess and secured therein at diametrically opposed points and presenting an annular edge depending from said heel and removed from 60 the side edges of said heel, and a resilient block mounted in said cup and fastened centrally thereto with the fastening means countersunk in said block, said block having a convex surface engaging the walls of said 65 cup and the remaining surface of said block being removed from the plane of the annular edge of said cup.

In testimony whereof I affix my signature in presence of two witnesses.

ROBERT J. BOYD.
